Primary Examiner — Carla J Wright*(74) Attorney, Agent, or Firm* — Allen, Dyer, Doppelt & Gilchrist, P.A.(57) **CLAIM**

The ornamental design for a phone grip accessory, as shown and described.

DESCRIPTION

FIG. 1 is a rear, top, left side perspective view of the design; FIG. 2 is a rear, top, right side perspective view of the design;

FIG. 3 is a rear, bottom, left side perspective view of the design;

FIG. 4 is a rear, bottom, right side perspective view of the design;

FIG. 5 is a rear view of the design;

FIG. 6 is a front view of the design;

FIG. 7 is a left side view of the design;

FIG. 8 is a right side view of the design;

FIG. 9 is a top view of the design; and,

FIG. 10 is a bottom view of the design.

Broken lines in FIGS. 1–4 illustrate environmental subject matter which forms no part of the claimed design. Broken lines in FIG. 6 illustrate boundaries of the claimed design and form no part thereof.

1 Claim, 8 Drawing Sheets(56)
